UNITED STATES PATENT OFFICE.

JESSE A. DUBBS, OF PITTSBURG, PENNSYLVANIA.

DISTILLING OIL.

SPECIFICATION forming part of Letters Patent No. 694,621, dated March 4, 1902.

Application filed February 28, 1901. Serial No. 49,268. (No specimens.)

To all whom it may concern:

Be it known that I, JESSE A. DUBBS, a citizen of the United States, residing at Pittsburgh, in the county of Allegheny and State of Pennsylvania, have invented or discovered certain new and useful Improvements in Distilling Oil, of which improvements the following is a specification.

In Letters Patent No. 646,639, granted to me April 3, 1900, I have described and claimed a method of distilling oil consisting, generally stated, in effecting the vaporization by the conjoint action of heat and air forced through the oil. Experience has shown that the distillate thus produced is defective for illuminating purposes by reason of the smoke and unpleasant odor produced in burning the distillate.

The object of the present invention is to provide for such a molecular change as will produce an oil which will be smokeless and odorless in combustion.

The invention is hereinafter more fully described and claimed.

In the accompanying drawings, forming a part of this specification, Figure 1 is a sectional elevation of a still suitable for the practice of my invention, and Fig. 2 is a similar view of a still adapted for the practice of a modification of the method.

In the practice of my invention the oil is charged into the still 1 and heated in the usual or any suitable manner to the temperature usual in distilling oils. Following the instructions set forth in Letters Patent No. 646,639 air is introduced through the pipes 3 and forced through the heated oil in regulated quantities. As before stated, the distillate thus produced is not satisfactory for illuminating purpose, as in combustion considerable smoke and an unpleasant odor are produced. It has been attempted to produce the molecular change necessary for the production of a distillate which in combustion will be free from smoke and odor by forcing air in excess of that believed to be necessary to effect distillation for the purpose of producing a further molecular change. Such excess of air so introduced did not produce any appreciable beneficial effect. I have ascertained, however, that if the distillate, whether in a

vaporous or liquid form, be subjected to the direct action of air that a further molecular change will be effected. This second distillation may be effected in several ways—as, for example, the liquid distillate may be placed in a still similar to the still 1 and a second distillation effected in the same manner as the first—that is to say, the distillate is heated in the usual or any suitable manner to a temperature to effect a vaporization of the oil, and air, preferably heated, is introduced through the pipe 3 and forced through the oil. The amount of air injected is controlled by the quantity of distillate escaping from the condenser. By determining the volume of gas at the temperature in the still necessary to produce a cubic foot of distillate the rate of flow of the distillate from the condenser will indicate the rate of evaporation in the still, as the gases flow freely from the still through the condenser. The rate of generation of gas being determined, the operator so adjusts the flow of air that the volume of the latter forced into the still during a given time will be about four times the volume of gas generated during the same period. In other words, the operator regulates the inflow of air in accordance with the flow of distillate from the condenser.

In lieu of condensing the vapors generated in the first or original distillation and then subjecting the distillate to a second treatment by air, air may be forced through the pipe 6 into the vapors contained in the upper portion of the still 1. The air thus introduced into the vapors will effect such a molecular change in the hydrocarbons that the oil will burn with a smokeless and odorless flame. In forcing air into the vapors in the upper part of the still 1 care should be taken that the proportions of air and vapor above stated should be maintained.

With some oils it may be necessary to subject them to three or more distillations—that is to say, the distillate from the crude is subjected to a distillation, as described, and the second distillate is subjected to a similar treatment. These successive distillations may be continued until the desired molecular change has been produced, which is determined by practical tests, such as burning the oil in a lamp. The successive treatments of the dis-

tillate may be effected either before or after the distillate has been condensed, as herein-before stated.

I claim herein as my invention—

5 1. As an improvement in the art of treating oils the method herein described, which consists in forcing air through the oil while the latter is maintained at a vaporizing temperature and then subjecting the distillate while heated to the action of air, substantially as set forth.

10 2. As an improvement in the art of treating oils the method herein described which consists in forcing air through the oil while the latter is maintained at a vaporizing temperature condensing the vapors, heating the distillate to a vaporizing temperature and forc-

ing air through the distillate while maintained at a vaporizing temperature, substantially as set forth.

20

3. As an improvement in the art of treating oils the method herein described which consists in forcing air through the oil while at a vaporizing temperature, subjecting the distillate while heated to the action of air and 25 similarly treating successive distillates, substantially as set forth.

In testimony whereof I have hereunto set my hand.

JESSE A. DUBBS.
